UNITED STATES PATENT OFFICE

2,507,378

REFRIGERATOR

Willard L. Morrison, Lake Forest, Ill.

Application July 27, 1945, Serial No. 607,289

8 Claims. (Cl. 62—89)

1

My invention relates to an improvement in refrigerators and is particularly adaptable to, but not limited to domestic electrical refrigerators.

One purpose is to provide a two temperature domestic refrigerator.

Another purpose is to provide a refrigerator in which a lower storage portion is formed or surrounded by a circumferentially extending evaporator, while the upper portion is located above said evaporator.

Another purpose is to provide improved means for controlling and varying the heat exchange between the evaporator of the refrigerator and the storage space surrounded by the evaporator.

Another purpose is to provide an improved for varying the heat exchange between the evaporator and the storage space in response to fluctuations of temperature in the storage space.

Another purpose is to provide an improved movable insulating member for the evaporator of a domestic refrigerator.

Other purposes will appear from time to time in the course of the specification and claims.

I illustrate the invention more or less diagrammatically in the accompanying drawings wherein:

Figure 1 is a vertical section;

Figure 2 is a section on the line 2—2 of Figure 1;

Figure 3 is a section on an enlarged scale on the line 3—3 of Figure 1;

Figure 4 is a section on a still further enlarged scale on the line 4—4 of Figure 3;

Figure 5 is a section on the line 5—5 of Figure 3;

Figure 6 is a section on the line 6—6 of Figure 3;

Figure 7 is a view of the parts shown in Figure 6 with the parts in a different position; and

Figure 8 is a partial vertical section illustrating a variation.

Like parts are indicated by like symbols throughout the specification and drawings.

Referring to the drawings 1 is any suitable base having lower downwardly extending strips 2. 3 is a disc of insulating material, such as fiber, cork or the like, mounted on the upper surface of the base 1. It may be positioned for example by a generally central dowel 2a which extends into appropriate recesses in the upper surface of the base 1 and in the lower surface of the insulating disc 3. 4 generally indicates an evaporator having a bottom wall 5, shown as having a downward extension 6 seated in a centering aperture 7 in the upper face of the insulating disc 3. Surrounding the exterior of the insulating disc 3 is an outer wall 8 which may be of sheet metal or any other suitable flexible material and which, when the refrigerator is completed, forms a cylindrical tensional outer hous-

2

ing member. Extending upwardly from the circumferential edge of the evaporator bottom wall 5, is an inner cylinder 9 and an outer cylinder 10. The two cylinders may be of sheet metal and define between them a space 11 which extends circumferentially about the evaporator and which receives a liquid refrigerant for evaporation. The cylinders 9 and 10 are shown as sealed together at their upper and lower edges as at 12 and 13 respectively. One of the cylinders, for example the outer cylinder, may be deformed to provide a series of circumferential passages or enlargements which are in communication with or form part of the space 11 between the two cylinders. I illustrate for example a lower enlargement 14, an intermediate enlargement 15, and an upper enlargement 16. Above the enlargement 16 the walls are sealed together as at 17. Above the sealed area is an additional enlargement 18 the interior of the space defined by which is separate from the space 11. The space within the enlargement 14 serves as a bottom distributing manifold 20 with an inlet member 21. The space within the enlargement 15 is an intermediate distributing space or manifold. The space within the enlargement 16 serves as a discharge manifold. In assembling the device the evaporator 4 is positioned as shown in Figure 1 and the outer housing or layer is positioned surrounding the disc 3 and engaging part of the outer periphery of the base 1. After the tubing which is below described is in position, relatively soft insulation 25 is firmly packed into the space between the outer wall 10 of the evaporator and the wall 8. The result is a provision of a firm self supporting structure. The upper surface of the insulation material 25 may be closed and compacted by any suitable ring or body 26 of somewhat firmer insulating material, such as fiber board. A layer of any suitable heat insulating material 27 may be positioned above it, it being important that no heat conducting material or members extend between the cylinders 8 and 10. Note also that the body or ring 27 extends inwardly above the upper edge of the evaporator. An upper finishing plate or ring 29 may be positioned upon the body 27, with its downwardly extending inner flange 30 spaced inwardly from and out of heat conducting relationship with the evaporator. The outer upwardly extending flange 31 of the ring 29 receives and centers any suitable inner shell 32 for the upper part of the refrigerator. An outer shell 33 is also employed, which is shown as extending downwardly about the upper edge of the outer cylinder 8 of the lower part of the refrigerator. Any suitable stiffening or supporting or bracing or spacing means 34 may be employed in the form for example of curved wooden strips. 35 indicates any suitable insulation between the

shells 32 and 33. The top of the upper refrigerator space may be covered by any suitable roof structure. I illustrate a roof having an outer shell 36, an inner or lower shell 37, and an intermediate insulating material 38. The top strip or strips 39 may be employed as shown in Figure 1. Any suitable door structure may be employed as shown in dotted line at 40 in Figure 1.

In the upper part of the refrigerator I illustrate an ice forming device shown in some detail in Figures 3 to 7. I illustrate for example an upper cold plate A and a lower cold plate B. The upper cold plate A is formed of an upper metal plate 65 and a lower metal plate 66. These plates are sealed at their edges as at 67 and are spaced apart and supported by intermediate braces or connectors 68. A central collar 69 defines an open interior passage 10. The space between the plates 65 and 66 is adapted to receive any suitable liquid refrigerant which may be circulated there through for evaporation. The plate B is similarly formed with an upper metal plate 65a, a lower metal plate 66a, a circumferential seal 67a, intermediate braces 68a and a central collar 69a.

71 is a stop bar extending upwardly from the cold plates A, B. It is adjustably threaded thereon to a nut which may contact the under surface 37 of the top of the refrigerator and thus limit the upward adjustment of the cold plate in assembly. The evaporator structure is carried by these supports and includes a bottom squared portion 73 welded or otherwise secured to the upper plate A. The upper portion of each support 72 is cylindrically formed and screw threaded as at 74 and suitably secured to the roof structure of the refrigerator, for example by any suitable nuts 75. Positioned on the freezing assembly is a combined drip pan and insulating device shown as consisting of an inner member 76 and an outer member 77 with any suitable insulating material 78 therebetween. The member 76 is shown as having an outwardly extending flange 79. 77a is any suitable handle. It will be understood that the insulating element is cup shaped and, when in its raised position, in which it is shown in Figure 6, substantially surrounds the entire evaporator structure, except for the upward exposure of the top plate. It may be held in raised position by any suitable supporting clips 50, shown as formed of spring stock and provided with detent portions 51 and lower outwardly bent handle or actuating portions 52. The member 50 is secured to a projection 53a from a sleeve 53 which has a square opening and is slideable on the squared portion of the support 72.

The member 53a is normally upwardly urged by the compression spring 54 which is coiled about the squared portion of 72 and abuts at its lower end against the top plate A and its upper end against the member 53a. 55 is an adjusting nut screw threaded on the upper portion 74 of the support 72, which is effective adjustably to limit the position of the member 53a and the sleeve 53. Assuming that the parts are in the position in which they are shown in Figure 6, the level at which the insulating structure, which I will generally indicate as D is held, is determined by the adjustment of the nuts 55. The insulating structure D is supported by gravity by the engagement of the flange 79 with the detent portions 51. If the user wishes to have access to the interior of the evaporator structure, for example to get access to the below described ice tray, the operator can pull down on the handle 77a. The insulating structure can then be tem-

porarily locked in downward position by the employment of the locking links 56 which are pivoted as at 57 to the top of the refrigerator and which have engaging notches 58 adapted to receive the upper portions of the members 50. When the parts are in the position in which they are shown in Figure 7 the compression of the springs 54 is effective to hold the parts as shown. However, a slight downward movement on the handle 77a will release the locking links 56. They will then swing by gravity to the vertical position in which they are shown in Figure 6 and the insulating cover D, when released will be lifted by the springs 54 to the position shown in Figure 6.

10 When it is desired to remove the insulating member D, as when it is desired to pour off the water which accumulates as a result of defrosting, the parts are first positioned as shown in Figure 7, and the user can then spread the members 50 and remove and drain the member D.

15 Within the space between the upper cold plate A and lower plate B, I may insert any suitable ice tray. I illustrate for example a tray including a bottom disc 130 and a circumferential side 25 wall 131. 132 is any suitable removable grid adapted to separate the water, when frozen, into ice cubes. 133 is a handle lug to which is pivoted as at 134 a bell crank lever having a handle component 135 with its handle bar 136 and a lifting component 137, the lower end of which engages the upper face of the lower plate B. It will be understood that a pull on the handle bar 136, causing the lever component 137 to move in a counterclockwise direction, will raise the bottom 30 130 of the ice tray and break the seal or frozen bond between it and the top of the lower evaporator cold plate B, permitting the ice tray to be readily removed. As will appear in Figure 3 only three of the vertical supports 71 and 72 are 35 employed, these being spaced 90° apart. Thus 40 180° of the space between the plates A and B is open, for the insertion and removal of the ice tray structure.

45 The lateral extension of the base 1, as at 1a serves as a machinery platform. The machine space is surrounded by any suitable louvered side wall structure 80 which includes vertical supports 81. 83 is a top wall or closure through which extends any suitable knob 84. Within the machinery compartment so formed I may position any suitable refrigerating mechanism. I illustrate for example a supporting bracket structure 85 which supports any suitable motor 86, and any suitable compressor 87. 88 indicates any suitable condenser which may be employed. 89 is any suitable control valve knob which is accessible through an aperture 83a in the wall 83. It is not normally employed by the user. 90 is a delivery duct along which condensed liquid refrigerant 50 may flow from the receiver 91. It is shown as 55 extending to the space or annular chamber within the enlargement 18. The spacer 18a, in the chamber causes the refrigerant to make a substantially complete circuit about the upper portion 60 of the refrigerator before it passes along the duct 92 to any suitable expansion valve 93 the details of which do not form part of the present invention. The refrigerant, at appropriately reduced pressure, flows along the duct 94 to the interior 65 of the bottom evaporator plate structure B. It passes thence by the duct 95 to the interior of the top evaporator plate structure A. It passes thence along the duct 96 to the distributor space 70 75 within the bottom enlargement 14 of the cylindrical evaporator. It will be understood

that the interior of the evaporator is so formed and proportioned that the unevaporated liquid refrigerant evaporates substantially uniformly throughout the space between the cylinders 9 and 10. The refrigerant, now largely or substantially entirely evaporated, escapes from the upper distributor space 22 along the return duct 100 to the compressor 87. From the compressor it passes by the duct 101 to the condenser 88 and thence by the duct 102 to the receiver 91. Any suitable control means may be employed, the details of which do not form part of the present invention. I illustrate for example a control bulb 93a for the expansion valve 93, connected thereto by any suitable duct 93b. The knob 84 may be employed, through any suitable actuating system, to control the temperature of the refrigerating system, the details of such control means not forming part of the present invention. Appropriate means may be employed whereby the operation of the system may be interrupted by a predetermined rotation or movement of the knob 84 for defrosting. It will be understood that, when this defrosting takes place the effect on the cold and well insulated lower evaporator 4 will be very slight and will be insufficient to raise the contents of the lower chamber within the evaporator indicated at C to dangerously near the freezing temperature. I may employ any suitable time limit means whereby, after a predetermined and relatively short period, the system returns to normal after the knob 84 has been set to the cut-off or defrosting position.

With reference to the use of the insulating sleeve or cup D, it is effective to prevent exterior frosting. In use, the exterior of the cup does not frost and that portion of the evaporator which is positioned below the plane of the lip of the cup frosts very little, if any at all. It is also effective as means for controlling the heat exchange rate between the evaporator structure in the upper compartment and the storage space of the upper compartment. It is normally set with its upper edge, at the general level of the flange 79, substantially even with the upper plate A. For example, it may be set somewhat below the top of the plate and the air which is chilled by the upper surface of the plate A may flow over the edge of the flange 79, and thus reach the storage space. If more cold is desired the nuts 55 are adjusted to lower the level of the upper edge of the insulating member D. If less cooling effect is desired the edge is raised, by raising the adjusting nuts 55. If the insulating member is left in the position in which it is shown in Figure 7 the cooling effect is correspondingly increased. But under normal circumstances it will be set substantially higher, the position of Figure 6 being a representative position.

With reference to Figure 8, I illustrate a variant form in which the insulating member D may be moved up or down, in response to variations in temperature of the storage space. It will be understood that the showing of Figure 8 is to be taken as diagrammatic or representative rather than as illustrating a commercial structure. I illustrate for example an adjusting sleeve 103 slideable on the evaporator support 104. The sleeve 103 is upwardly thrust by the spring 105 against the limit member 106 which is slideable upon the upper portion 107 of the support. The insulating member D is supported by a detent and supporting element 108 substantially identical with that shown at 50, 51 and 52 in Figure 6. The position of the member 106 is controlled by a lever

109 pivoted intermediate its ends as at 110 to any suitable supporting lug 111. One end of the lever 109 is provided with pins 112 extending into a circumferential groove portion 113 in the member 106. The other end may be slotted as at 114 to receive a pin 115 on the piston shaft 116 which extends through the piston head 117 and supports a piston 118 within the cylinder 119 to which the piston head 117 is secured. Positioned within the cylinder 119 is any suitable expandable liquid 120 which expands or contracts in response to changes in temperature. It will be understood in the structure as shown, that as the temperature in the storage space drops, the liquid 120 contracts and the piston 118 may move toward the lower end of the cylinder 119. This permits the limit member 106 to rise, in response to the thrust of the spring 105, and the result is a lifting of the insulating member D, which reduces the amount of heat absorbed by the evaporator structure from the upper storage space. Similarly, a rise in temperature expands the liquid 120 and causes the lever 109 to move the limit member 106 downwardly against the compression of the spring 105, with a consequent lowering of the insulating member D, and an increase in the cooling effect. As a matter of convenience the cylinder 119 may be secured to the inner side wall 121 of the upper part of the storage chamber.

It will be understood that a variety of heat responsive actuating means may be employed for the member 106, and the lever transmission is indicated somewhat diagrammatically as illustrating a typical means for varying the position of the adjusting member 106 in response to variations in the temperature of the storage space of the upper half of the refrigerator.

It will be realized that, whereas, I have described and illustrated a practical and operative device, nevertheless many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of the invention are as follows:

I use the movable insulating member D, encompassing a cold element A, B, located at the top of a refrigerator. By adjusting the position of the encompassing insulating member D, the temperature of the space being cooled can be varied because of the fact that the cold element A, B suspended in the very top of the refrigerator may be variably exposed by the element D. The cooled air spills into or fills the insulated member D, and flows over its edge to the space being cooled. Any change in the level of the top edge of the cup D causes it to encompass more or less of the cold element A—B, with a resultant drop or rise in temperature in the space being cooled. This differs from the present apparatus used in household refrigerators because, in order to adjust the temperature in the present household refrigerator, it is necessary to control the cycling of the refrigerating machine. That is to say, to make the storage space colder, it is necessary to have the machine run longer and make the evaporator colder. With the herein described apparatus it may be seen that if the user wishes to have the cold element much colder, perhaps for the purpose of freezing ice cube trays rapidly, he can avoid freezing the space 70 being cooled by raising the upper rim of the

cup member. The change in storage temperature is obtained by changing the position of the cup member D.

It will be understood, from the description I have made of the new device, that I gain a tremendous advantage by being able to have the cold element A, B, in the upper portion of a refrigerator much colder than would be possible without the encompassing cup member D, and the important result is that because I make the cold member colder without freezing the upper part of the refrigerator or the space where the food is being stored, I can therefore freeze ice cubes much faster without freezing food in the upper portion of the refrigerator.

I claim:

1. In a refrigerating apparatus, an insulating housing surrounding a storage space, an evaporator positioned in said storage space, means for circulating a volatile refrigerant through said evaporator, an open topped container adapted to surround the sides and bottom of said evaporator and means for guiding it for movement upwardly and downwardly about said evaporator, said container being adapted to maintain a pool of cold air about said evaporator, whereby frosting of the portion of the evaporator positioned in said pool of cold air is substantially prevented and yielding means tending normally to urge said container toward a predetermined upper position.

2. In a refrigerating apparatus, an insulating housing surrounding a storage space, an evaporator positioned in said storage space, means for circulating a volatile refrigerant through said evaporator, an open topped container adapted to surround the sides and bottom of said evaporator and means for guiding it for movement upwardly and downwardly about said evaporator, said container being adapted to maintain a pool of cold air about said evaporator, whereby frosting of the portion of the evaporator positioned in said pool of cold air is substantially prevented and yielding means tending normally to urge said container toward a predetermined upper position and adjustable abutment means adapted to limit the upward movement of said container.

3. In a refrigerating apparatus, an insulated housing enclosing a storage space, an evaporator located within the storage space, means for circulating a volatile refrigerant through the evaporator, an insulating cover closely enveloping the evaporator to positively limit the area of evaporator surface exposed to heat exchange relationship with the storage space, and means for displacing said cover to vary the area of such exposed evaporator surface whereby the heat exchange relationship is varied.

4. In a refrigerating apparatus, an insulated housing enclosing a storage space, an evaporator located within the storage space, means for circulating a volatile refrigerant through the evaporator, an insulating cover closely enveloping the evaporator to positively limit the area of evaporator surface exposed to heat exchange relationship with the storage space, and thermostatically controlled means for displacing said cover to vary the area of such exposed evaporator surface whereby the heat exchange relationship is varied in consonance with variation in the temperature within the storage space.

5. In a refrigerating apparatus, an insulated housing, closed at the top, enclosing a storage space, an evaporator located in the upper por-

tion of the storage space below the top of the housing, means for circulating a volatile refrigerant through the evaporator, a combined insulator and drip cup, and means for holding said cup in position to closely mask the bottom and side walls of the evaporator, the evaporator being thus exposed in heat exchange relationship with the storage space at its top surface only, and means for lowering the cup to increase the area of exposed evaporator surface.

6. In a refrigerating apparatus, an insulated housing, closed at the top, enclosing a storage space, an evaporator located in the upper portion of the storage space below the top of the housing, means for circulating a volatile refrigerant through the evaporator, a combined insulator and drip cup, and means for holding said cup in position to closely mask the bottom and side walls of the evaporator, the evaporator being thus exposed in heat exchange relationship with the storage space at its top surface only, supporting means for the cup adapted to hold the cup selectively in raised position to partly enclose the evaporator to the storage space, yielding means whereby the cup may be removably detached from the supporting means for withdrawal from the storage space.

7. In a refrigerating apparatus, an insulated housing, closed at the top, enclosing a storage space, an evaporator located in the upper portion of the storage space below the top of the housing, means for circulating a volatile refrigerant through the evaporator, a combined insulator and drip cup, yielding means for holding said cup in position to closely mask the bottom and side walls of the evaporator, stop means adapted to be set to hold the cup in lower position to unmask the sides of the evaporator and thereby expose a larger area of evaporator surface to heat exchange relationship with the storage space.

8. In a refrigerating apparatus, an insulated housing, closed at the top, enclosing a storage space, an evaporator located in the upper portion of the storage space below the top of the housing, means for circulating a volatile refrigerant through the evaporator, a combined insulator and drip cup, yielding means for holding said cup in position to closely mask the bottom and side walls of the evaporator, stop means adapted to be set to hold the cup in lower position to unmask the sides of the evaporator and thereby expose a larger area of evaporator surface to heat exchange relationship with the storage space, the evaporator including two parallel cold plates, an ice tray removably positioned between them, the cup, when in the upper position, completely masking the tray.
